UNITED STATES PATENT OFFICE.

ABRAHAM W. GOLDMAN, OF LOS ANGELES, CALIFORNIA.

WINDOW SASH AND SCREEN.

Application filed January 19, 1926. Serial No. 82,201.

My invention is a window sash and screen embodying a frame having a sliding balanced sash and with a screen incorporated in the frame forming stops for the sash.

5 An object of my invention is the construction of a simple type of window frame with sliding sashes, the frame utilizing a minimum amount of lumber and giving a balanced sash.

10 The sashes are balanced by having an inner and an outer sash connected together by flexible chains or the like, whereby both sashes operate in unison when one is raised the other being lowered.

15 A further object of my invention is forming a window frame with a screen on the outside thereof, the screen being detachable and allowing ready removal of the outer sash, the screen also being adapted to form stops or guides for the outer sliding sash.

20 Another object of my invention is to construct a screen having a metal covering, the metal forming a holding connection between the screen and the window frame.

25 With my type of window frame having a balancing sash with a screen forming a stop for the sash the building construction whether of brick, wood or plaster may be constructed up close to the stile of the frame.

30 Another feature of my invention is the double pulleys used for balancing the sashes; these being constructed with a sheet metal frame or casing and pulley wheels mounted therein, the frame being supported in addition to wood screws passing through the pulleys by the central bead of the sash.

35 My invention will be more readily understood from the following description and drawings, in which;

40 Figure 1 is an inside view of a window frame constructed in accordance with my invention.

Fig. 2 is an outside view showing the screen with the metal edge covering.

45 Fig. 3 is a side elevation in the direction of the arrow 3 of Fig. 2.

Fig. 4 is a vertical section on the line 4—4 of Figs. 1 or 2.

50 Fig. 5 is a detail cross-section through one of the side bars of the screen on the line 5—5 of Fig. 4.

Fig. 6 is an elevation of the double pulley sash chain.

55 Fig. 7 is a cross-section of the pulleys on the line 7—7 of Fig. 6.

Fig. 8 is a detail showing the form of hook for attaching the chain to a sash.

Fig. 9 is a further detail of the type of hook taken at right angles to Fig. 8.

The window frame is constructed substantially as follows, having reference particularly to Figs. 1 to 4:

A sill 1 extends across the bottom of the frame, preferably being inclined at an angle slightly downward and outwardly to give a rain drip.

Single boards 2 forming stiles extend outwardly from the sill and are joined by a cap rail 3, this being formed of a single board. The sill extends outwardly beyond the outer edge of the stiles as indicated by the numeral 4 and has an outward projection 5 on its outer end on the wall portion; this being adapted to extend beyond the wall line of the building.

Inside stops 6 are attached to the stiles and similar stops 7 and 8 to the sill and cap rail respectively. A center bead 9 is fitted preferably in a rabbet 10 on the top rail and on the stiles. This forms a separating guide for the inner and outer sashes.

The sashes themselves are of substantially the ordinary construction, the inner sash being designated by the numeral 11 sliding between the stops 6, 7 and 8 and the center beads 9. The outer sash 12 is slideable on the outside of the center beads. The sashes are balanced by means of a sash chain 13 which passes over the double pulley assembly 14 secured to the top of each stile thereby balancing the sash.

The screen is constructed as follows, being illustrated particularly in Figs. 2, 3 and 4, being designated generally by the numeral 15:

The screen is formed with a lower rail 16, an upper rail 17 and side bars 18 connecting the upper and lower rails. A wire screen 19 is placed on the face of the frame so formed. A sheet metal covering 20 is placed on the outside of the rail 16 covering the lower edge of the screen and a sheet metal strip 21 is utilized to cover the side bars. The top rail 17 is also covered by an angular sheet metal strip 22.

The strip 21 is formed angular having a return bend 23 covering part of the side of the side bars and having a flange 24 covering part of the front edge of the frame stiles 2. A wire screen is secured directly

on the face of the screen framing and is held in place by nails, screws or the like driven through the sheet metal strips on the face of the screen framing.

The screen is held in position by means of a cross bead 25 secured to the cap rail 3 at the outer edge thereof, a return bend 26 of the metal strip 22 having a flange 27 engaging behind the bead. A hook and eye 28 secured to the lower rail of the screen and to the window sill holds the base of the screen in place.

The construction and manner of supporting the double pulleys is substantially as follows, being illustrated particularly in Figs. 6 and 7:

A sheet metal frame forms a housing for the pulleys and has a flat face 29, edge walls 30, backwardly bent sections 31 and forwardly bent ends 32; these ends engaging the face plate 29. The housing so formed is open at the top 33 and at the bottom 34. A pair of pulleys 35 are secured in the pulley frame by means of wood screws 36 inserted through openings in the sheet metal of the frame and through the axial center of the pulleys. These screws form the journals for rotation of the pulleys. The upper ends of the inturned edges 32 have a cut-out section 37 allowing the sash chain 38 to pass freely up one side of the frame and across the top and down the other side.

It will be noted that in the assembly of the sash in the window frame the center bead 9 engages the lower edge of the pulley frame or housing and the center bead 10 engages the face 29 of the pulley housing; this construction being illustrated in Figs. 1 and 4. Therefore, although the pulley housing is constructed of very light material and supported by comparatively small screws, it is so secured in place by the stops that a heavy weight may be hung therefrom, thereby allowing a hanging of a heavy balanced sash.

I utilize a hook 39 on the end of the sash chain, this hook being formed by a wire having a loop 40 therein and oppositely bent hooked ends 41, these latter being curled around a wood screw 42 or the like.

From the above description of the window frame and sash it will be seen that there is no outside bead or stop guiding the outer sliding sash, this being done by the frame of the wire screen, thereby effecting a saving in material and allowing the window to be of less thickness from the outside to the inside of the building.

The removable screen also allows the

outer sash to be swung outwardly on the sash chains, the hooks to be disconnected and the sash bodily removed if desired. The inner stop 6 is also readily removable thereby allowing removal of the inner sash. As the sashes may thus be readily removed from the window frame, they may be installed in the reverse manner.

Although my invention is a comparatively simple form of window frame and balanced sash having a screen cooperating therewith, it is to be understood that the general construction and specific details could be changed to suit different installations, such changes being within the spirit of my invention as set forth in the description, drawings and claims.

Having described my invention, what I claim is:

1. A window comprising in combination a window framing, an inner and outer sliding sash mounted therein, a bead separating said sashes and a screen fitting directly against one of the sashes and holding same in position.

2. A window comprising in combination a window framing, a sliding sash mounted therein, a cross bead at the top of the frame outside the upper portion of the sash, a window screen having a sheet metal cover at its upper portion, the cover being bent to engage behind the bead, the window screen engaging the sash and holding same in place in its sliding movement.

3. A window comprising in combination a window frame having side stiles and a cap rail, a sliding sash mounted therein, a window screen having side bars, an upper and lower rail, a sheet metal covering on the side bars, said covering on the side bars being bent and having edges on the outside of the window stiles.

4. A window comprising in combination a window frame having side stiles, a cap rail and a sill, a sliding sash mounted therein, a window screen having side bars and upper and lower rails, sheet metal covering in the side bars and upper rail, the covering on the side bars being bent and having edges extending over the window stiles, a cross bead secured to the cap rail, the covering on the upper rail of the screen being bent underneath the said bead and means to secure the lower end of the screen, the screen forming a guideway for the sliding sash.

In testimony whereof I have signed my name to this specification.

ABRAHAM W. GOLDMAN.
